DESIGN FOR A FENDER GUIDE KNOB OR SIMILAR ARTICLE

Bert G. Cochrane, Chicago, Ill., assignor to Casco
Products Corporation, Bridgeport, Conn., a
corporation of Connecticut

Application January 13, 1938, Serial No. 74,270

Term of patent 14 years

To all whom it may concern:

Be it known that I, Bert G. Cochrane, a citizen
of the United States, residing at Chicago, in the
county of Cook and State of Illinois, have in-
vented a new, original, and ornamental Design
for a Fender Guide Knob or Similar Article, of
which the following is a specification, reference
being had to the accompanying drawing, forming
part thereof.

Figure 1 is a front view of the fender guide

knob or similar article, showing my new design.

Fig. 2 is a side view of the same.

Fig. 3 is a rear view of the same.

The knob of my design is also adapted to be
used as a gear shift knob, radiator cap ornament,
fender ornament, and bumper ornament.

I claim:

The ornamental design for a fender guide knob
or similar article, as shown and described.

BERT G. COCHRANE.
